UNITED STATES PATENT OFFICE.

ELMER C. DITTMAR, OF WILLIAMSPORT, PENNSYLVANIA.

METHOD OF COATING AND FINISHING FLOORING.

Original application filed August 28, 1918, Serial No. 251,740. Patent No. 1,339,107. Divided and this application filed November 20, 1918. Serial No. 263,359.

To all whom it may concern:

Be it known that I, ELMER C. DITTMAR, a citizen of the United States, residing at Williamsport, in the county of Lycoming 5 and State of Pennsylvania, have invented certain new and useful Improvements in Methods of Coating and Finishing Flooring, of which the following is a specification, reference being had therein to the accompanying drawing.

This invention relates to a method of coating and finishing flooring and is a companion application of my application filed November 20, 1918, Serial 263,358 and comprises a division of my application filed August 28, 1918, Serial No. 251,740, the object being to provide a machine by means of which the flooring filled and varnished in the companion case can be given a coating 20 of oil and additional coating of varnish so as to complete the finishing of the flooring strip.

Another object of the invention is to provide novel method of applying a coating 25 of oil to the under face of the flooring strip as it passes through the machine so that the entire surface of the strip will be coated in order to preserve the strip when in use.

Another and further object of the invention 30 is to provide a method for smoothing the surface thus treated so that the last coat of varnish can be applied without brush marks, whereby I am able to obtain a high finish without applying a smoothing powder thereto.

Other and further objects and advantages 35 of the invention will be hereinafter set forth and the novel features thereof defined in the appended claims.

In the drawings,

Figure 1 is a side elevation of the apparatus for coating and finishing flooring.

Figure 2 is a top plan view of the same.

Figure 3 is an end view and a section 45 taken on the line 3-3 of Figure 1.

Figure 4 is a detail vertical section through one of the guide rollers.

Figure 5 is an elevation partly in section of the varnish tank and tray.

Figure 6 is a vertical section through a portion of the endless conveyor.

Figure 7 is a top plan view of the same.

Figure 8 is a vertical section through the oil tray.

Figure 9 is a detail perspective view of 55 the lower end of the oil feed pipe.

Figure 10 is a vertical section through the pressure roll bearing, partly in elevation.

Figure 11 is an elevation, partly in section, 60 of one of the pressure rolls.

Figure 12 is a perspective view showing the manner of mounting the burnishers, and

Figure 13 is a section showing the manner 65 of securing the brushes to the holder.

In constructing an apparatus for carrying 70 out my method of coating and finishing flooring, I employ a frame 1 which is provided with a horizontally disposed guide-way 2, in which is mounted one of the runways of an endless conveyor 3, carried by sprockets 4 mounted in adjustable bearings 5, as clearly shown in Figure 1. One of the sprockets is mounted on a shaft 6, journaled in suitable bearings in the frame 1, and having a tight and loose pulley 7 and 8 75 mounted thereon which are adapted to be driven by a drive belt 9 from any suitable source of power, not shown.

The endless conveyor 3 is driven by a shaft 6 so as to move in the guide-way which 80 is formed of such a width that it receives snugly a strip of flooring 10 to be operated on. The conveyor is provided with spurs which are adapted to engage the under side 85 of the strip 10, the strip adapted to be forced against the conveyor by pressure roller 11, carried by a shaft 12 mounted in an adjustable bearing 13 which is engaged by an arm 14 carrying a weight 15 in order to apply the proper pressure to the strip.

Mounted about the conveyor in advance of the pressure roller 11 are a series of burnishers 16 preferably formed of glass mounted in blocks 17 carried by flexible holders 18 which are pivotally connected to supports 19 95 and are provided with screws 20 for adjusting the pressure. The contacting surfaces of the burnishers are so constructed that they do not scrape the surface but burnish the previously varnished strip. While in this apparatus I have shown this construction of holder for the burnishers, the construction shown in my companion application can be used, and I do not wish to limit myself to the use of any particular construction of 100 105 burnisher as I have found in practice that other styles can be used in order to accomplish the same results.

Arranged in the same horizontal plane as the conveyor at the opposite end of the frame are supports 21 having adjustable guide rollers 22 between which the strip of material 5 being operated on is adapted to pass, and these rollers are preferably grooved so as to support the strip in such a manner that the upper and lower surfaces of the strip can be readily coated, as will be later described.

- 10 Mounted on a suitable bracket extending from the frame 1, is an oil tray 23 in which is adjustably mounted the perforated block 24 having its upper surface covered with cloth 25 which is adapted to apply the coat 15 of oil to the under surface of the strip as it passes over the same. The tray 23 is formed with open ends which are bent to form guide-ways 26 so as to guide the strip of flooring as it passes through the same.
- 20 In order to remove the surplus of oil I provide the block 24 with leather strips 27 which engage the under surface of the strip of flooring after it has been coated with oil so as to force the oil into the pores and to re- 25 move the same therefrom.

The oil tray 23 is supplied with oil from a tank 28 by a pipe 29, which is provided with a slot 30 said pipe extending down into the tray in such a manner that the oil will 30 be maintained at a predetermined level therein and prevented from overflowing by atmospheric pressure.

Pivotaly mounted on the frame 1, is a varnish tray 31 which is provided with a reduced lower portion 32 having an apertured bottom over which is arranged a strip of felt 33 which is adapted to be held in contact with the upper surface of the strip of flooring by pressure through the medium of 40 a weight 34 so as to apply the last coat of varnish to the strip. The varnish tray 31 is supplied with varnish from the varnish tank 35 through a pipe 36 which extends into the reduced portion of the tray, and is provided 45 with an opening 37 in order to maintain the varnish in the tank at a predetermined level. This prevents the varnish from hardening as only a small amount of varnish is maintained in the tray.

- 50 After the strip of flooring has been given a coat of varnish it passes under a pair of brushes 38 carried by a brush holder 39, pivoted to the frame 1 so as to apply the varnish evenly to the surface as the strip passes 55 through the machine.

In order to hold the strip firmly against the cloth in the oil tank I arrange a pair of pressure rollers 40 to each side of the oil tray, said rollers being held under tension 60 by coiled springs 41, as shown in Figure 11.

As a strip of material which has been previously varnished and allowed to dry is fed onto the endless conveyor it first passes under the burnishers where all rough portions are 65 removed, and as it passes under the pressure

roller 11 is forced into engagement with the endless conveyor in such a manner that it is carried forward through the oil tray and under the varnish tray. As the strip is only driven by the endless conveyor when the end 70 thereof leaves the conveyor the movement stops until it is engaged by the next strip, and this prevents the strips from being carried out from under the varnish tray until the next strip has passed under the same, 75 thereby eliminating any waste.

In the drawings I have shown details of construction but I do not wish to limit myself to these various details of construction, as the main object of my invention is to provide an apparatus for carrying out the method of coating the under surface of a strip of lumber with a preservative and the upper surface with varnish in such a manner that all hand work is eliminated. 80

What I claim is:

1. The method of finishing a previously varnished strip of flooring consisting in moving the strip in a normal path, burnishing the strip and then applying to the surface 90 thereof a coating of varnish.

2. The method of finishing strips of previously coated lumber consisting in continuously moving the strip of lumber and while in motion applying a coat of varnish to the 95 surface of the strip and then by the movement of the strip subjecting the coating of varnish thus applied to a brushing action to form a smooth surface.

3. The method of finishing strips of 100 previously varnished flooring consisting in burnishing the surface of the strip to remove the roughened portions therefrom, applying a coating of varnish to the upper surface of the strip under pressure and then brushing 105 the varnish to form a smooth surface.

4. The method of finishing a previously varnished strip of flooring consisting in imparting movement to the strip, burnishing the upper surface of the strip, applying a 110 coating of varnish to the upper surface, and brushing the varnish to produce a smooth surface.

5. The method of finishing a previously varnished strip of flooring, consisting in 115 moving the strip in a normal path, burnishing the upper surface of the strip, and then applying a coating of varnish to the upper surface thereof under pressure.

6. The method of finishing a previously 120 varnished strip of flooring, consisting of moving the strip in a normal path, burnishing the upper surface of the strip, then applying a coating of varnish to the upper surface of the strip, and spreading the varnish thus 125 applied to form a smooth surface.

7. The method of finishing strips of previously coated lumber consisting in moving the strip in a normal path, burnishing the strip, applying additional coating to the 130

strip, and then brushing said coating to form a smooth surface.

8. The method of finishing strips of previously coated lumber consisting in continuously moving the strip of lumber and while in motion applying a coat of varnish to one face of the strip and simultaneously applying a coating of waterproof composition to the other surface of the strip.

10. 9. The method of finishing strips of previously coated lumber consisting in continuously moving the strip of lumber in a normal path and while in motion applying a second coating of varnish to the previously 15 varnished surface of the strip and simultaneously applying a coating of waterproof

composition to the unvarnished surface of the strip.

10. The method of finishing strips of previously varnished flooring consisting in 20 burnishing the surface of the strip while in motion, applying a coating of varnish to the surface of the strip while in motion, and then spreading the varnish thus applied to form a smooth surface.

25 In testimony whereof I have hereunto affixed my signature in presence of two witnesses.

ELMER C. DITTMAR.
